UNITED STATES PATENT OFFICE.

OSSIAN T. WAITE, OF OSHKOSH, WISCONSIN.

DESIGN FOR A GRASS RUG.

51,825.

Specification for Design. Patented Feb. 26, 1918.

Application filed January 4, 1918. Serial No. 210,369. Term of patent 3½ years.

To all whom it may concern:

Be it known that I, OSSIAN T. WAITE, a citizen of the United States, residing at Oshkosh, in the county of Winnebago and State of Wisconsin, have invented a new, original, and ornamental Design for Grass Rugs, of which the following is a specification, reference being had to the accompanying drawing, forming part thereof, which exhibits in plan a view of my new rug design.

I claim:

The ornamental design for a grass rug, substantially as described.

OSSIAN T. WAITE.
